UNITED STATES PATENT OFFICE.

THEODORIC JONES, OF DALLAS, TEXAS.

TRAFFIC SIGNAL.

1,415,362.

Specification of Letters Patent.

Patented May 9, 1922.

Application filed June 18, 1921. Serial No. 478,583.

To all whom it may concern:

Be it known that I, THEODORIC JONES, a citizen of the United States, residing at Dallas, in the county of Dallas and State of 5 Texas, have invented certain new and useful Improvements in Traffic Signals, of which the following is a specification.

This invention relates to new and useful improvements in traffic signals.

10 The invention has particular to do with a signal device adapted to be mounted on the side of an automobile and operated by the driver thereof. The object of the invention is to provide a traffic signal of the swinging 15 arm kind which may be operated and fastened in position in a simple and effective manner. Another object is to provide illumination for the signal hands. A further object is to provide a device which may be 20 employed on an open car or on a closed car.

A particular feature of the invention resides in a sliding and rotating operating rod co-operating with a fastening device and having universal connection with the signal 25 arm, whereby it may be slid and also rotated.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is a front view of an automobile 35 equipped with signals constructed in accordance with my invention, a portion of the automobile being broken away to show the operating member and the signal arm being shown in different positions in full and 40 dotted lines,

Fig. 2 is a longitudinal sectional detailed view of the signal device,

Fig. 3 is a cross sectional detail of the locking member,

45 Fig. 4 is a face view of the same,

Fig. 5 is a detail showing the electrical contact connections, and

Fig. 6 is a view of the arm rest for the signal.

50 In the drawing the numeral 10 designates a rectangular casing having its upper and outer sides open. The inner side of the casing is closed by a wall 11 and the casing is provided with a bottom 12. A bracket 13 attached to the bottom of the casing is also employed to fasten said casing to the sup-

port 14 which may either be the body of an open car or the body of a closed car. The support is provided with a slot 15 registering with an aperture 16 in the wall 11. 60

A signal arm 17 which may be in the form of a rod or bar and which is preferably tubular, is pivoted at its inner end on the studs 18 mounted in the front wall of the casing 12. On the outer end of the arm a suitable signal 65 device such as a hand 19 is mounted. This hand is provided with a suitable display opening 20 through which an incandescent lamp 21 is exhibited. This lamp is connected with wires A and B which extend 70 through the arm 17. The wire B has connection with the casing 12 and is suitably grounded, while the wire A is connected with a spring contact arm 22 mounted on the hub of the arm 17 and suitably inflated therefrom. The contact arm 22 engages a segment 23 which has connection with a suitable 75 source of electrical current from the automobile.

Near its pivot the arm 17 is provided with 80 a lug 24 to the outer end of which is pivoted a link 25. The link 25 has a ball 26 on its end engaging in a socket 27 on the outer end of an operating bar 28 which extends through the slot 15 of the aperture 16. 85 The inner end of the bar 28 extends within the automobile and has a crank handle 29 fastened on its end. A locking collar 30 is fastened to the inner side of the support 14 and the bar 28 passes through this collar. 90 The collar is provided with an arcuate cam 31 and a slot 32 above its central opening, said cam starting at the slot, and having a notch 31' at its opposite end.

It will be seen that by pushing or pulling 95 the cam 28 so as to move it longitudinally, the arm 17 will be swung in a vertical arc. When the bar 28 is pulled inwardly to its limit, the arm 17 will be swung to an upright position and will engage in the rest 33 100 which is fastened to the windshield or side of the body. In order to hold the arm in this position, the bar 28 is provided with a lug 34 adapted to slide through the slot 32. By turning the handle lever 29 downwardly the 105 lug 34 will ride over the cam 31 and drop into the notch 31' at the end, whereby the member 28 will be held against outward displacement and the arm 17 will be held in upright position.

When it is desired to make a turn the handle 29 is rotated so as to bring the lug 110

34 in registration with the slot 32 which permits the bar 28 to be moved outwardly. The bar is moved outwardly until a second lug 35 thereon is brought into position to 5 ride over the cam surface 31 and catch in the notch when the bar is rotated. The arm 17 will thus be supported in the intermediate position shown in dotted lines. By repeating the operation and moving the bar 38 10 outwardly until a third lug 36 is engaged in the notch 31', said arm 17 is held in a horizontal position indicating a stop.

It will be seen that the ball and socket joint 26 and 27 permits the bar 28 to be 15 freely rotated. To assist in swinging the arm 17 I provide a spring 37 which is coiled about the stud 18 and has one end engaging under the arm 17 and its other end engaging in one of the series of apertures 38 in the 20 casing 12. By changing the engagement of the spring with the apertures 38, the tension of the spring is regulated. It will be seen that this spring tends to lift the arm and, therefore, when it is desired to swing said 25 arm 17 upwardly the operator will be assisted by the spring. Also in lowering or swinging the arm 17 downwardly the spring will prevent a sudden and jerky movement of the latter.

30 Various changes in the size and construction of the parts as well as modifications, may be made without departing from the spirit of the invention.

What I claim is:

35 1. In a traffic signal, a support adapted for attachment to an automobile, a signal arm pivoted to said support to swing in a vertical arc, an actuating bar pivotally and rotatively connected with the arm, and fastening means actuated when the member is 40 rotated for holding said member against outward displacement and maintaining the signal arm in position.

2. In a traffic signal, a support, an arm pivoted on the support and adapted to swing 45 in a vertical arc, an operating bar having connection with the arm and arranged to slide longitudinally and to rotate, and a fastening device through which the bar passes engaged by the bar when the same is ro- 50 tated.

3. In a traffic signal, a support, an arm pivoted on the support and adapted to swing in a vertical arc, an operating bar having connection with the arm and arranged to 55 slide longitudinally and to rotate, a fastening device through which the bar passes engaged by the bar when the same is rotated, and a supporting spring connected with the arm and arranged to be adjusted 60 whereby its tension is varied.

4. In a traffic signal, a support, a vertical swinging arm carrying a signal device and pivoted on the support, an electric lamp carried by the arm, electric circuit connection for the lamp, means for raising and lowering said arm and fastening the same in adjusted positions, and a rest engaged by the arm and supporting it in its upright position. 70

5. In a traffic signal, a support, a signal arm pivoted on the support and arranged to swing in a vertical arc, a signal device carried by the arm, a longitudinally movable operating bar, said bar having a ball and 75 socket connection with the signal arm for swinging the same, means on the inner end of the bar for rotating the same, a fastening collar through which the bar slides provided with a cam, and lugs in spaced relation on the bar for engaging behind the cam to fasten the signal arm in adjusted positions. 80

In testimony whereof I affix my signature.

THEODORIC JONES.
